DESIGN FOR A DISPLAY STAND

Frederick W. Nichol, New York, N. Y., assignor to
International Business Machines Corporation,
New York, N. Y., a corporation of New York

Application October 9, 1940, Serial No. 95,727

Term of patent 14 years

To all whom it may concern:

Be it known that I, Frederick W. Nichol, a citizen of the United States, residing in New York, in the county of New York and State of New York, have invented a new, original, and ornamental Design for Display Stands, of which the following is a specification, reference being had to the accompanying drawing, forming part thereof.

Fig. 1 is a front view of a display stand, showing my new design, the opposite side showing substantially the same appearance.

Fig. 2 is a top plan view of the same.

I claim:

The ornamental design for a display stand, substantially as shown and described.

FREDERICK W. NICHOL.
